UNITED STATES PATENT OFFICE

OSCAR SCHLICHTER, OF HAMILTON, OHIO, ASSIGNOR TO KRAUTH & BENNINGHOFFEN,
OF HAMILTON, OHIO, A FIRM

PAPER FEED FOR TYPEWRITERS

Application filed October 20, 1928. Serial No. 313,911.

This invention relates to an improvement in typewriter attachment for supporting and unreeling multi or a plurality of webs preferably from a single roll to and upon a platen or writing table, whereupon the webs are compiled in a superposed arrangement for manifolding purposes. The webs contain form printing and the forms of the several webs are relatively aligned, set in registry, and clamped upon the table in position for typing.

The improvements primarily are directed to a type of machine as disclosed in an earlier application filed by me May 24, 1927, Serial No. 193,919, with the general features embodied therein incorporated herein.

In this type of machine, the several webs are drawn from a multi web supply roll, each individually passing over a floating gravity roller and thence over a guide roller in a fixed journal, directing the web in a plane with the writing platen or table.

The present improvement relates to the interposition of paper gripping rollers between the gravity and guide rollers and between which all of the webs pass to hold the same against retrograde motion, thereby relieving the served portion of the webs upon the writing table against potent backward strains of the floating tension rollers and permitting the webs to be freely drawn in a forward direction.

It is, therefore, an object of my invention to provide simple and effective means for gripping the supply webs after withdrawn from the supply roll, to withhold the same normally against retrograde motion, self-freeing with the forward feed of the webs, and releasable at will, for backing the webs, in making the adjustment of the webs upon the writing table.

Another object of the invention in a machine of the character herein referred to, is to journal a plurality of guide rollers as a unit upon a hinged bearing frame capable of being swung from its normal horizontal position in plane with the table to a vertical or at an angle to the table for accessibility to the rolls in threading the webs thereover when loading the machine.

Other features and advantages of the invention will be more fully set forth in the description of the accompanying drawings forming a part of this specification, in which:

Figure 1 is a top plan view of the device 55 with the webs loaded therein.

Figure 2 is a section on line 2—2, Figure 1.

Figure 3 is an end view of a portion of the rear end of the machine embodying the present improvements.

Figure 4 is a section on line 4—4, Figure 3.

Figure 5 is a detailed end view of the web gripping mechanism.

The mechanism primarily provides a web support, platen and pedestal for Elliot 65 Fischer typewriting or billing machines, the typewriter being translatable supported upon the pedestal above the platen, the upper sides of the machine serving as tracks therefor.

The webs in the plural number are single roll wound. This form of supply roll being merely a convenient method for merchandising and use, is supported in a suitable support below the table portion of the machine, and the several webs are suitably unreeled, each web individually passing over a floating tension roll, thence between gripping rolls to guide rolls directing the webs in plane with the table, and thence upon and over the writing platen, bringing the webs in superposed arrangement upon the platen for manifolding purposes, and whereupon they are held under tension and in registry as to their form printing, so that they can be suitably typed upon. The webs can be conveniently drawn forwardly and the advanced or delivered portions torn from the strips or webs across a tearing blade at the forward end of the machine.

The platen mechanism and the method for clamping and holding the sheets or webs upon the platen and the control therefor is substantially the same as that shown and described in the aforesaid application, being 95 treadle operated, the treadle in the present instance also serving to control the gripping rolls for separating the rolls in backing the webs.

Referring to the drawings, 1—1 indicates 100

side frames held together by cross rods 2—2 and cross bars 3—3 to form a pedestal structure for supporting the printing platen 4 and typewriter, the typewriter, not shown, being 5 translatable supported upon the side rails 6—6 extending rearwardly of the pedestal and from which the web supply roll or rolls is dependingly supported.

10 A roll of multi-web paper 8 is hung beneath the frame of the machine on depending brackets 9. The brackets 9 are dovetailed into the side frames 6—6 and bound together by a tie rod 10. Their lower ends are slotted to provide hooks engaging the respective 15 ends of a shaft or spindle 11 supporting the roll 8 and rotatable therewith.

10 A U-shaped rack 12 is pivoted to the side frames 6—6 and is disposed at the feed side of the roll and toward the end of the device. 20 The rack is of such length as to clear the floor beneath the machine and is rigidly maintained in position, slanting away from the roll by means of a pair of arms 12^a.

25 The arms 12^a, one at each side of the rack, are pivoted thereto as at 12^b and extend to the brackets 9. Pairs of slots are provided in the arms and adapted to engage over pins on the bracket 9. One pair of these slots, namely, 12^c, maintains the rack in service 30 position and another pair 12^d is for sustaining it out from below the machine during loading of the roll.

35 The rack is fabricated of stampings to provide opposingly related slots 13 in its side arms in which a plurality of horizontally disposed rollers 14 are slidably mounted. The rollers have reduced end portions engaging the slots, the shoulders formed thereby preventing longitudinal displacement of the rollers. The number of rollers 14 corresponds to the number of webs of paper in the 40 roll. The side arms of the rack are formed of pairs of flat pieces spaced apart by the lower cross piece and spacer plates at the top to provide the slots 13 and formed at the top to 45 encircle the pivot studs.

50 Above the rack and between the side frame or rails 66—66, a plurality of parallel guide rolls 15 are journaled in a journal frame 16 hingedly secured to the side rails 6, adapting the guide rollers as a unit with the journal frame to be swung from the normal position in plane with the writing platen upwardly to a vertically inclined position, rendering the 55 rollers more accessible in engaging the webs thereover when loading the machine.

50 A pair of paper gripping rolls are interposed between the gravity tension rollers 14 and the guide rollers 15, arranged to permit the webs to be drawn in a forward direction for advancing the webs and locked against any backward or reverse motion, so that the served portion of the paper is free from the depressing weight of the tension rolls when 65 making the adjustment of the several webs.

upon the writing table as to their form registry and alignment and in engaging the paper upon pins at the forward end of the writing platen, after which the gripping rolls can be positively released or separated to offer free movement of the paper in a reverse direction, allowing the paper to be drawn back under the weights of the tension rollers to take out the slack, drawing the served portion tautly over the writing platen.

70 The gripping rolls comprise a roll 17 having its opposite ends journaled in brackets 18—18 fixed to the rack frame 12 and a short width eccentric roll 19 fixed upon the shaft 20, the shaft 20 having its opposite ends 80 journaled in the brackets 18—18.

75 The roll 17 preferably sustains the full width of the paper, while the eccentric roll only engages the central portion thereof and is positioned to come in wedging contact with the paper and roll 17 under any backlash of the paper or when the forward pull or advance of the paper is stopped, so that the webs are bound or clamped between the rolls, with the served portion relieved of the 90 weight of the tension rollers 14.

85 The roll 17 at one end is provided with a pinion 21 fixed to its axis and in mesh with a pinion 22 loose on shaft 20 of the eccentric roll 19. A pawl lever 24 is fixed on the end 95 of the shaft 20 adjacent the loose pinion 22 and carries a pawl 25 engaging with the teeth of the pinion 22, the pawl 25 locking the pinion against reverse rotation.

90 The roll 17 is free to rotate with the forward feed or travel of the paper which also releases the eccentric roll, allowing the paper to be withdrawn from the supply roll, the pinions idling during the forward travel of the paper, and as soon as the pull on the paper is stopped the eccentric roll under the influence of the tension rolls drops back into contact with the roll 17, gripping the paper.

100 To release the rolls 17 and 19, the pawl lever 24 is rocked by a treadle 26 connecting with the pawl lever through a cable 27 having one end fixed to the treadle, at its opposite end to one end of the pawl lever, and guided over an idler sheave 28 journaled on the pedestal.

105 Depressing the treadle 26 rocks or swings the pawl lever, revolving the pinions 21 and 22 through the pawl 25 engaging with the teeth of the pinion 21. The eccentric roll 19, with the rotation of the pinion 22 in an appropriate direction upon the pressing of the treadle, swings away from contact with the roll 17, releasing the webs between the rolls. The means for applying the necessary friction to the spindle of the supply roll, and the 110 platen mechanism, is substantially as described in the aforesaid application. Therefore, complete detail description thereof is 115 herein omitted.

120 The platen 4 has its rear end depressible by 130

5 a lever mechanism mounted beneath the platen operatively connected with the treadle 26, and in its normal position forcibly bears against a pair of stationary clamp lugs or fingers 29 at opposite sides of the platen which grip the opposite edges of the paper upon the platen, clamping the paper to the platen.

10 Pins 30—30 are provided at the forward end of the writing platen for engagement through apertures in the webs, the pins serving as guides for bringing the webs into relative alignment and the preprinted forms thereon into registration, and also positively anchors the forward end of the webs. The apertures are provided at definite spacing longitudinally of the webs and bear a relation to the preprinted form lengths.

15 A hingedly mounted cross plate 33 having a tearing edge extends across the forward end of the writing platen and is operated to engage over the pins and in connection with the lever mechanism beneath the writing platen for actuating the writing platen, and thus the cross plate is under the influence of the spring pressure, moving the platen in its normal position for holding the webs against displacement from the pins.

20 For advancing the paper from one form length to a second or the distance of the aperture spacing to bring the subsequent forms of the several webs in position upon the writing platen, the treadle is depressed, which raises the forward cross plate and depresses the rear end of the writing platen when releasing the paper, so that it can be disengaged from the pins and drawn forwardly a required amount. The depression of the treadle likewise actuates the pawl lever for 25 the gripping rolls, releasing the gripping rolls, freeing the paper of its grip, which is guided over the gripping roll 17 from the floating rollers to the guide rollers in line with the printing platen.

25 Thus, the full weight of each respective tension roller is upon its web, thereby applying the necessary tension for unreeing the webs from the supply roll and for drawing the same tautly over the writing platen when engaged with the pins preliminary to locking or clamping the paper upon the platen by the cross plate and clamp fingers. Since the pressure on the treadle is released, the eccentric roll 19 moves into contact with its companion gripping roll 17, locking or withholding the webs against reverse motion or feed under the weight of the tension rollers, and relieves the paper beyond the gripping rolls of the pressure of the tension rolls.

30 Having described my invention, I claim:
 1. In a device of the character disclosed, a frame, a platen mounted in said frame for supporting one or a plurality of webs in superposed relation for manifolding, a journal and spindle carried by the frame beneath

the platen for supporting a multi-web wound supply roll of paper, guide rollers journaled in said frame, one for each web of the supply roll, guiding an unreeled portion of the webs from beneath the platen to and in plane with the platen, a pair of gripping rolls in the path of the web between said guide rollers and supply roll and between which the webs pass, said gripping rollers cooperating to prevent retrograde motion of the webs, and floating rollers, one for each web, each bearing upon a respective web for applying tension upon the web between the gripping rolls and supply roll.

2. In a device of the character disclosed, a frame, a platen mounted in said frame for supporting a web of paper, a journal and spindle carried by the frame beneath the platen for supporting a supply roll of paper, a pair of gripping rolls in the path of an unreeled portion of the web extending to the platen, cooperating to grip the web and prevent retrograde motion thereof, and a floating roller bearing upon and applying tension on the web between the supply roll and gripping rolls.

3. In a device of the character disclosed, a frame, a platen mounted in said frame and supporting a web of paper, means carried by the frame for supporting a supply roll of paper, a pair of gripping rolls in the path of an unreeled portion of the web to the platen from the supply roll, said rolls cooperating to grip the web and prevent retrograde motion thereof, a floating roller bearing upon and applying pressure on the web between the supply roll and gripping rolls, and means for throwing said gripping rolls out of cooperation, extending the floating roller pressure to the web portion upon the platen beyond said gripping roll for backing up the web and drawing the same tautly upon the platen.

4. In a device of the character disclosed, a frame, a platen mounted in said frame and supporting a web of paper, means carried by the frame for supporting a supply roll of paper, a pair of gripping rolls in the path of an unreeled portion of the web to the platen from the supply roll, said rolls cooperating to grip the web and prevent retrograde motion thereof and allowing free forward motion to the web, tension means for applying pressure on the web between the supply roll and gripping rolls, and means for throwing said gripping rolls out of cooperation, extending the retarding pressure to the web portion upon the platen beyond said gripping roll for backing up the web and drawing the same tautly upon the platen.

5. In a device of the character disclosed, a frame, a platen mounted in said frame and supporting a web of paper, a pair of gripping rolls in the feeding path of the web to the platen from the supply source, said rolls cooperating to grip the web and prevent

retrograde motion thereof, a floating roller bearing upon and applying pressure on the web between the supply source and gripping rolls, and means for throwing said gripping rolls out of cooperation, extending the floating roller pressure to the web portion upon the platen beyond said gripping roll for backing up the web and drawing the same tautly upon the platen.

6. In a device of the character disclosed, a frame, a platen mounted in said frame for supporting a web of paper, means for applying a retarding pressure upon the web as it leaves its supply source, a pair of gripping rolls in the feeding path of the web to the platen from the supply source, respectively comprising an eccentric roll and a concentric roll, cooperating to grip the web and prevent retrograde motion thereof, gearing transmittingly connecting said rolls, adapting said rolls to be revolved with the forward motion of the web for non-impeding the feed of the paper, pawl mechanism engaging with one of said gears, and means for actuating said pawl in a direction for positively rotating said gears for roll separation, adapting the web retarding pressure to be extended to the portion upon the platen for backing-up service in adjusting the web upon the platen and drawing it tautly over the platen.

In witness whereof, I hereunto subscribe my name.

OSCAR SCHLICHTER.
